UNITED STATES PATENT OFFICE

133,074

DESIGN FOR A HANDKERCHIEF

Maria Rass, New York, N. Y.

Application June 15, 1942, Serial No. 107,207

Term of patent 3½ years

To all whom it may concern:

Be it known that I, Maria Rass, a citizen of the United States of America, residing in New York city, county of New York, and State of New York, have invented a new, original, and ornamental Design for a Handkerchief, of which the following is a specification, reference being had to the accompanying drawing, forming part thereof, wherein,

The figure of the drawing is a plan view of a handkerchief showing my new design.

I claim:

The ornamental design for a handkerchief, substantially as shown.

MARIA RASS.
